Atty.

UNITED STATES PATENT OFFICE.

BURT B. BREWSTER, OF SALT LAKE CITY, UTAH, ASSIGNOR TO SULLIVAN MACHINERY COMPANY, A CORPORATION OF MASSACHUSETTS.

STANDARD FOR ROCK DRILLS.

Application filed October 26, 1918. Serial No. 259,846.

To all whom it may concern:

Be it known that I, BURT B. BREWSTER, a citizen of the United States, residing at Salt Lake City, in the county of Salt Lake 5 and State of Utah, have invented certain new and useful Improvements in Standards for Rock Drills, of which the following is a full, clear, and exact specification.

This invention relates to standards, and 10 more particularly to standards used in mines for supporting drilling apparatus adapted for drilling blasting holes or shot holes, the object of the present invention being to provide an inexpensive, light, adjustable, folding support for retaining in a horizontal or other desirable position a hammer drill and steel for drilling shot holes.

These and various other objects have been accomplished in the present invention, a 20 practical embodiment of which is shown in the accompanying drawings, in which

Fig. 1 is a side elevation showing the standard supporting a hammer drill and a steel in operative position.

Fig. 2 is a plan view of the same.

Referring to the drawing and to the embodiment of my invention therein disclosed, I have shown for illustrative purposes a standard 1, composed of a crosshead 2, connected at its center through a T coupling 3 with a substantially horizontally disposed leg 4, the crosshead 2 being supported at the ends thereof by two angularly disposed bracing and supporting legs 5 which contact 35 with the mine floor.

These supporting legs 5 are made in two parts 6 and 7, the part 6 consisting of a solid rod of metal or other suitable material, having on one end a suitable point 8 adapted 40 to keep the end of the rod 6 from sliding along the mine floor, and the part 7 consisting of a hollow tube connected at one end to the crosshead by means of a curved coupling member 9 and adapted to receive 45 telescopically the rod 6, and to retain this rod in adjustable relation therewith by means of a set screw 10. The couplings 9 hold the legs 5 at such an angle to the crosshead that these legs brace the crosshead and 50 leg 4 against rearward or sideward movement.

The substantially horizontally disposed

leg 4 has a pointed end 11 to retain this end at a predetermined point on the face of the coal 12 or other material to be mined. 55 Two bent rods 13 and 14 depend from the horizontally disposed leg 4 and serve to retain a hammer drill 15 and a drill steel 16 received in the socket of the chuck of the drill in parallel relation with said leg 4, the bent rod 13 having hook shaped ends 17 adapted to receive the handle 18 of the hammer and the bent rod 14 having a loop or hook 19 to receive and guide the steel. The rod or support 13 may be slid along the horizontally disposed leg 4 to feed the drill steel into the coal but the rod or support 14 is preferably rigidly attached to the leg 4 to assist in guiding the steel when starting the hole. 70

When in use the operator adjusts the length of the bracing and supporting legs 5 so that the leg 4 is held in a substantially horizontal position with the pointed end thereof in spaced relation above the place 75 where the hole is to be drilled. To drill the hole, it is only necessary to guide the drill by movement of the handle 18 and to press on the handle to hold the drill steel against the work. When the operator desires to 80 transport the drilling mechanism and standard to another position, he dismounts the hammer drill and steel and folds the standard by rotating the leg 4 until it is in the plane of the legs 5. 85

While I have shown and described my standard as supporting a tool in a position for drilling a horizontal hole, it is to be understood that the standard may be adjusted to drill the hole at any angle to the 90 face of the material to be mined, and while I have herein shown and described for the purpose of illustration one specific form of the invention, it is to be understood that the same has been chosen for illustrative purposes only and that extensive deviations may be made from the disclosed form thereof without departing from the spirit of the invention or the scope of the appended 95 claims.

What I claim as new and desire to secure by Letters Patent is:

1. In combination with a hand portable rock drilling apparatus comprising a drill

steel and a tool for causing the same to drill a hole, said tool having a socket loosely receiving said steel, a mounting for said apparatus comprising a standard having 5 legs, and spaced means supported on one of said legs for respectively suspending the steel and tool therefrom during drilling.

2. In combination with a hand portable self-contained rock drilling apparatus comprising a drill steel and a tool for causing the same to drill a hole, said tool having a socket loosely receiving said steel, a mounting for said apparatus including a standard having legs, and means supported on one of 10 said legs and adapted to engage said tool and steel and hold the same with their axes in parallelism with said leg during drilling.

3. In combination, a drill steel, a self-contained power operated hand tool adapted 20 to cooperate therewith and having a chuck loosely receiving said steel, and means for suspending said steel and tool during drilling comprising a standard having legs and means freely slidable along one of said legs and adapted to engage and support said tool during drilling, and means connected to said leg and supporting said drill steel as the latter enters the face.

4. In combination, a drill steel, a self-contained power operated drilling tool adapted 30 to cooperate therewith and having chuck means loosely receiving the steel, and means for supporting said steel and tool during drilling comprising a standard having a leg adapted to be supported against the face to be drilled, means supported on said leg and slidable therealong and adapted to 35 readily engage and support said tool, and means connected to said leg and disposed adjacent said face for slidably supporting said drill steel.

5. In combination, a standard having a leg thereon adapted to be disposed against the surface to be worked, and means depending from said leg for supporting the usual 45

manual grasping handle of a hand drilling tool.

6. In combination, a standard having a leg thereon adapted to be disposed against the surface to be worked, and means depending from said leg for supporting the usual manual grasping handle of a hand drilling tool, and means carried on said leg for supporting a steel actuated by said tool. 50

7. In combination, a standard having a leg thereon adapted to be disposed against the surface to be worked, and means depending from said leg including a pair of hooked ends adapted to support the handle of the tool. 55

8. In combination, a standard having a leg thereon adapted to be disposed against the surface to be worked, depending hooked means slidable on said leg and adapted to support the handle of a tool, and depending means carried on the front end of said leg adapted slidably to receive a steel. 60

9. In combination, a standard having a leg thereon adapted to be disposed against the surface to be worked, means slidable on 70 said leg and having depending laterally spaced hook-shaped ends adapted to support the handle of a tool, and means carried on the front end of said leg having a depending portion adapted to support a tool 75 steel.

10. In combination, a standard having a leg engageable with the face to be worked, a portable drill having a manual grasping handle and a drill steel, means slidable on 80 and depending from said leg adapted to receive the drill handle, and cooperating means depending from said leg adapted slidably to receive the drill steel, said means constituting the sole means for supporting 85 said drill and steel on said standard during drilling.

In testimony whereof I affix my signature.

BURT B. BREWSTER.
